BOTTLE

Rudolph P. Kunett, West Hartford, Conn.

Application November 29, 1950, Serial No. 13,179

Term of patent 14 years

(Cl. D58—6)

To all whom it may concern:

Be it known that I, Rudolph P. Kunett, a citizen of the United States, residing at West Hartford, in the county of Hartford and State of Connecticut, have invented a new, original, and ornamental Design for a Bottle, of which the following is a specification, reference being had to the accompanying drawing, forming part thereof.

In the drawing:

Fig. 1 is a front elevational view of a bottle, showing my new design;

Fig. 2 is a rear elevational view thereof;

Fig. 3 is a top plan view thereof; and

Fig. 4 is a bottom plan view thereof.

I claim:

The ornamental design for a bottle, as shown.

RUDOLPH P. KUNETT.
